UNITED STATES PATENT OFFICE.

ARTHUR G. G. GUENTHER, OF CHICAGO, ILLINOIS, ASSIGNOR TO SIGNODE SYSTEM, INC., OF CHICAGO, ILLINOIS, A CORPORATION OF DELAWARE.

STRETCHING TOOL.

Application filed July 25, 1918. Serial No. 246,665.

to all whom it may concern:

Be it known that I, ARTHUR G. G. GUENTHER, a citizen of the United States, residing at Chicago, in the county of Cook and State of Illinois, have invented an Improvement in Stretching Tools, of which the following is a specification.

This invention relates to stretching tools for stretching box strapping or the like, and has among its objects the production of a tool of extreme simplicity in construction and operation which may be employed efficiently to stretch box strap applied about a box or other package.

To permit an understanding of the invention, I have illustrated one embodiment thereof in the accompanying drawings, but without thereby limiting the invention to such embodiment.

In the drawings:—

Fig. 1 is a cross sectional elevation of the tool on the line 1—1 of Fig. 3;

Fig. 2 is an elevation partly in cross section;

Fig. 3 is a plan view of the tool;

Fig. 4 is a cross sectional plan view on the line 4—4 of Fig. 1;

Fig. 5 is a cross sectional end elevation on the line 5—5 of Fig. 1.

In the particular illustrative embodiment of the invention shown in the drawings, a portion of the box or other package to be strapped is represented by the reference character 1, the package being surrounded by box strapping 2, whose ends 3 and 4 are overlapped.

The tool selected as an illustrative embodiment of the invention is shown in Figs. 1 and 2 as applied to the strap 3 and 4.

The tool comprises a lower gripping element 5 placed underneath the overlapped strap ends, and a feed wheel 6 resting upon them. The stretching operation is performed by the intermittent rotation of the feed wheel 6 in the direction indicated by the arrow in Fig. 1 under the influence of pumping operations of the handle 7, the result being to feed the upper strap end forward while the lower is held stationary with respect to the gripper 5, and thereby to tighten the strap upon the box.

The tool as a whole comprises a main frame 10 arranged in a vertical plane. This frame is supported at the rear on the thin flanges 11 and at its forward end upon the

gripper element 5, which constitutes a sort of rocking foot, and for this reason has an extremely advantageous operation, as will be described. Journalled in the main frame 10 at its rounded forward end 12 is the shaft 13 which carries welded thereto at one end, and over the gripper element 5, the feed wheel 6. The strap ends are gripped between the feed wheel 6 and the gripper element 5. To contribute to this result, the gripper element 5 is carried on two curved arms 17, which are pivotally mounted on a bolt 16 in an enlargement 15 of the main frame 10, above and behind the shaft 13. These curved arms 17 project forwardly at their upper ends as indicated at 18 for convenient manual manipulation, and at their lower ends are curved forwardly and formed integrally with the gripper 5, which directly underlies the shaft 13. The gripper 5 is recessed, and inset therein is a hardened steel, toothed plate 20 secured thereto by a screw 21. Since the feed wheel 6 is likewise toothed on its periphery, it will be apparent that the overlapped strap ends 3 and 4 will be effectively gripped and engaged between the gripper 5 (through its toothed plate 20) and the toothed surface of wheel 6.

In the operation of the tool, as the feed wheel forces the top strap end in the direction of the arrow (Fig. 1), the wheel 6 tends to roll to the right, thus sliding the whole tool to the right on the box Fig. 1. This produces a pull of the lower strap end on the grip 5, pulling this member to the left relatively to the tool (Fig. 1). Since the gripper 5 is hung eccentrically with respect to the central shaft 13, the gripper 5 and the periphery of the feed wheel 6 will be forced continually into tighter engagement as the stretching progresses. In other words, the tool is supported at its forward end on a sort of rocking foot comprising the gripper 5, adapted to cooperate with the relatively stationary feed wheel to grip the strap, and the tension of the lower strap on the rocking foot causes the latter to bind against the feed wheel 6 with a force proportionate to the tension. This affords an automatic grip of the strap proportioned to the requirements of each stage of the operation; eliminates the necessity for manual adjustment during the stretching, and provides for as heavy a grip as is necessary at the last stage of the operation without any

of the disadvantages inherent in the use of heavy springs or the like.

To hold the gripper 5 normally lightly in engagement with the feed wheel 6, I provide a spring 25 mounted on a lug 26 secured on the plate 10 and bearing against the rear of one of the arms 17. This engagement may immediately be released by the operator's pushing with his thumb on the extension 18 when it is desired to apply the tool to the strap. In releasing the tool from the strap, even when the same has been stretched, the operator merely pushes forwardly on the projection 18, and lifts the tool slightly at the same time (though the latter movement is not necessary), whereupon the grip will at once be released and the tool can be removed. Since the spring 26 is light the releasing operation is very simple. It does not require the overcoming of all the pressure on the strap ends as in the case where the grip is effected by the direct action of a spring.

I will now describe the means for intermittently rotating the feed wheel 6:—Referring to Figs. 1, 2, 4, and 5, rotatably mounted upon the shaft 13 and secured thereon as by the nut 30 is the disk 31, from which extends the integral arm 32, to which is secured the handle 7, the handle being secured by the interior split collar and screw apparatus indicated at 33—34 to permit replacement by a handle of another length. Between the disk 31 and the shaft 13 I interpose a roller clutch. The disk 31 has formed integrally with it the cylindrical flange 35, in which is inset the hardened ring 35', which encloses the ratchet clutch member 36 having teeth 37, while in the recesses of the clutch member 36 are interposed the rollers 38. Thus, for every downward (clockwise, Fig. 1) movement of the handle 7 (Fig. 1) the rollers 38 (by a well-known wedging action) will cause a partial rotation of the ratchet clutch member 36, while the handle may be moved in the other direction to any extent without affecting the ratchet clutch member. The clutch member 36 is secured upon a squared portion 39 of the central shaft 13 so that the rotation of the clutch member 36 rotates the shaft 39 and therefore of course rotates the feed wheel 6 welded upon said shaft.

In order to provide hold-back means to hold the strap under whatever tension has been attained during the return stroke of the handle, I make use of another roller clutch. For this purpose, a ratchet clutch member 41 is welded to the plate 10 concentrically with the shaft 13. The clutch member 41 has teeth 42 thereon faced oppositely to the teeth 37 previously described. Integrally on the feed wheel 6 is a cylindrical flange 43 having inset therein a hardened ring 43' overlying the clutch member 41,

and in the recesses of the ratchet 41 are placed rollers 44. It will be obvious that with this construction the feed wheel 6 cannot move backwardly, inasmuch as any backward movement will cause one or other of the rollers 44 to wedge upon the stationary central ratchet member 41 secured to the plate 10. Only three teeth are shown on this hold-back ratchet 41 extending about half way around the ratchet clutch member 41 because in any ordinary position of the tool, i. e., when the same is either laid upon the top or applied to one of the vertical sides of the box, three such teeth covering half the circumference of the ratchet member 41 will insure at least one of the rollers being in position immediately to wedge should the feed wheel 6 be rotated backwardly. It is of course obvious, however, that the teeth 42 could be extended all around the ratchet 41, but for the ordinary use of the tool, teeth extending half way around the wheel are adequate and more economical.

In the operation of the tool, the operator by pressing the extensions 18 rocks back the arms 17 against the spring 25 so as to separate the gripper 5 and the feed wheel 6, whereupon the tool is slipped sidewise onto the overlapped ends of the strap and (when the projections 18 are released) grips them between the toothed plate 20 on the gripper 5 and the feed wheel 6, while a flange 11 at the other end of the tool is laid under one of the lengths of strap, as shown in Fig. 1. The operator now starts to move the handle 7 up and down with a pumping action; at each downward motion of the handle, the feed wheel 6 is partially rotated. The result of this will be to feed the upper reach of strap forwardly or in the direction of the arrow in Fig. 1, while the lower strap end 3 is held by the gripper element 5. The resulting tension pulls the gripper 5 and the feed wheel 6 into tighter engagement owing to the eccentric mounting of the gripper 5 with respect to the center of the feed wheel.

In actual operation, it will be found that the tool creeps backwardly as it is used to stretch the strap since the feed wheel 6 pulls the upper end 4 of the strap thus causing tension to be developed, tending to pull the tool to the right, until the tension on the lower strap end 3 is substantially the same as that upon the upper strap end 4. This result is of practical value, because it exposes a substantial portion of the overlapped strap ends to the left of the tool in a position where a reinforcing girth may easily be applied thereto, maintaining the actual engagement of the tool with the strap only where the gripper 5 engages the lower strap, i.e., near its end, and exposing all the rest of the overlap. The same creeping movement obviously causes the grip on the strap

ends to become progressively tighter. To permit this creeping movement the flange 11 is made thin and smooth upon its bottom so that it can ride readily backward under the influence of the operation of the machine. When the strap is stretched, the ends thereof are joined by any suitable means, preferably as by a joint disclosed in Patent No. 1,252,680, granted to Ellsworth E. Flora, 10 January 8, 1918. To remove the stretching tool, it is merely necessary to lift upward slightly on the forward end of the tool and at the same time push the extensions 18 so as to rock the arms 17 counter-clockwise 15 (Fig. 1). This opens the jaws of the tool so that it may be easily slipped sideways off the stretched and joined strap.

Having now described my invention, I claim:—

20 1. A stretching tool of the class described comprising means to engage overlapped strap ends and feed them longitudinally in opposite directions, said means being adapted automatically to grip the strap ends between them with a grip varying according to the tension of the strap.

25 2. A stretching tool of the class described comprising a feed wheel adapted to engage and advance one end of the strap, a movable retainer to engage the other, said retainer being adapted to move during the stretching operation.

30 3. A stretching tool of the class described comprising a strap feeding element and a gripping element adapted to cooperate with the strap feeding element to feed the strap ends longitudinally relatively in opposite directions, the gripping element being movably mounted and adapted to move in the stretching operation.

35 4. A stretching tool of the class described comprising a strap feeding element and a gripping element adapted to cooperate with the strap feeding element to feed the strap ends longitudinally relatively in opposite directions the gripping element being movably mounted and adapted to move in the stretching operation, and means whereby the gripping element may be released from the strap.

40 5. A stretching tool comprising a support, a strap feeding member for feeding a strap end longitudinally, a gripping member adapted to grip the strap in combination with the feeding element, the gripping element being so constructed and arranged with respect to the strap feeding element as to maintain engagement with the strap varying with the tension thereof.

45 6. A stretching tool comprising strap engaging means adapted to move the strap ends relatively one past the other and to develop thereby forces tending to move the stretching tool longitudinally of the strap, said means being adapted to be forced into

tighter engagement with the strap by said forces.

7. A stretching tool comprising a support, a strap feeding member mounted in the support, a gripper member adapted to underlie the effective portion of the strap feeding member, said gripper member being pivotally mounted on an axis offset sideways from a position above the effective portion of the strap feeding member. 75

8. A stretching tool for box strapping comprising a support, a strap feeding wheel mounted in the support, a gripping member adapted to cooperate with the strap feeding wheel and pivotally mounted on the support eccentrically with respect to the feeding wheel. 80

9. A stretching tool comprising a support, a strap feeding wheel mounted in the support adjacent one end thereof, said support having a foot spaced from said wheel and a gripping member adapted to cooperate with said wheel and pivotally mounted on the side of the axis of said wheel toward said foot. 90

10. A stretching tool of the class described, comprising a stationary foot to support the tool at one end and a rocking foot to support the tool at the other end and a feeding element adapted to cooperate with the rocking foot. 95

11. A stretching tool of the class described, comprising a stationary foot to support the tool at one end and a rocking foot to support the tool at the other end and a feeding element adapted to cooperate with the rocking foot and resilient means to hold the rocking foot normally in engagement with the feeding element. 100

12. A stretching tool comprising a support, a feed wheel journaled in the support, a gripper pivoted to said support and cooperating with the feed wheel, an operating lever and a roller clutch interposed between the lever and the feed wheel. 110

13. A stretching tool comprising a support, a shaft journaled in the support, a feed wheel mounted rigidly on the shaft, a gripper pivoted to said support and cooperating with the feed wheel, an operating lever journaled on the shaft and a clutch interposed between the lever and the shaft. 115

14. A stretching tool comprising a support, a shaft journaled in the support, a feed wheel mounted rigidly on the shaft, a gripper pivoted to said support and cooperating with the feed wheel, an operating lever journaled on the shaft, a clutch element rigid on the shaft and a cooperating clutch element on the operating lever. 120

15. A stretching tool comprising a support, a shaft journaled in the support, a feed wheel mounted rigidly on the shaft, an operating lever journaled on the shaft. 130

a ratchet toothed wheel rigid on the shaft, a flange on the operating lever enclosing said toothed wheel and rollers in the recesses of said toothed wheel.

5 16. A stretching tool comprising a support, a feed wheel journalled in the support, a gripper cooperating with the feed wheel, an operating lever and a roller clutch interposed between the lever and the feed 16 wheel, a hold back roller clutch between the support and the feed wheel to maintain the feed wheel against being drawn backwardly.

15 17. A stretching tool of the class described comprising a support, a gripper element mounted on the support, a shaft journalled in the support, a feed wheel fixed on the shaft, an operating lever journalled on the shaft on the side of the support opposite the feed wheel, a roller clutch between the operating lever and the shaft for intermittently rotating the latter, a second roller clutch interposed between the support and the feed wheel to prevent backward rotation of the feed wheel.

18. A stretching tool comprising a sup-

port, a gripper element mounted on the support, a shaft journalled in the support, a feed wheel fixed on the shaft, an operating lever journalled on the shaft on the side of the support opposite the feed wheel, a clutch between the operating lever and the shaft for intermittently rotating the latter, a second clutch interposed between the support and the feed wheel to prevent backward rotation of the feed wheel.

19. In a stretching tool and in combination, a support, a gripping element, a feeding element, an operating handle, a pair of roller clutches one cooperating with the handle and the feeding element, the other with the support and the feeding element.

20. In a stretching tool a support, a gripping element, a feed wheel, an operating handle, a pair of overrunning clutches, one of said clutches co-operating with the handle and the feed wheel, the other clutch co-operating with the support and the feed wheel.

In testimony whereof, I have signed my name to this specification.

ARTHUR G. G. GUENTHER.
